UNITED STATES PATENT OFFICE.

JABEZ P. HENRIES, OF MOUNT VERNON, NEW YORK.

CASTER.

SPECIFICATION forming part of Letters Patent No. 670,426, dated March 26, 1901.

Application filed July 21, 1900. Serial No. 24,428. (No model.)

To all whom it may concern:

Be it known that I, JABEZ P. HENRIES, a citizen of the United States of America, residing at Mount Vernon, in the county of West-
5 chester and State of New York, have invented certain new and useful Improvements in Casters, of which the following is a specification.

My invention relates to an improvement in casters, and more particularly to so-called
10 "ball-bearing" casters, the present invention having provision for cushioning the main ball of the caster.

The primary object of the invention is to reduce the friction to a minimum; and with
15 this in view the invention consists, in the main, of a ball adapted to rest upon the floor, antifriction-balls which rest upon this main ball, cushioning means, and ball-retainers constructed and adapted to confine the main
20 ball in place and to yield under the weight of the furniture in order to recede slightly from the main ball and prevent friction thereon as far as possible.

In the accompanying drawings, Figure 1 is
25 a perspective view showing my improved caster applied to the leg of a piece of furniture. Fig. 2 is a view in vertical section. Fig. 3 is a bottom plan view of the caster with the main ball removed, and Figs. 4 and 5 are
30 bearing-plates.

A represents a ferrule of sheet or cast metal, in the interior of which lugs 11 are formed in pairs equidistant from one another. These lugs are beveled or rounded off on their outer
35 edges by preference, and between the pairs of balls 88 are confined. These balls 88 rest upon the main caster-ball 9, constituting antifriction-bearings therefor. Above the lugs 11 and resting thereon means is provided for
40 retaining the balls in the sockets formed by the lugs, and this means consists of the bearing-plates 5 and 5', (shown separately in Figs. 4 and 5, respectively,) but which might be made in one piece, if preferred. As shown,
45 the lower plate 5' is provided with a central concavity 7, which arches over the main ball 9, as shown in Fig. 2, and affords clearance therefor. At equidistant points in this plate 5' the holes 5" are made, they being adapted
50 to register with the openings formed between the lugs of each pair. The other plate 5 has a central hole 5a to receive the concavo-con-

vex portion 7 of the lower plate. Likewise this plate 5 has recessed seats 66 formed therein. These seats 66 are placed immediately above the openings 5" in the plate below, and unitedly the openings 5" and the seats 66 afford sockets for the antifriction-balls 88. As previously stated, the same results could be obtained by making these two plates in one and providing them with the concavity 7 at the center and the several sockets 66 at the edges in position to lie above the space formed between the lugs on the inner wall of the ferrule.

Immediately above the plates 55' a washer 11 is placed. This washer is of elastic material and constitutes a yielding backing for the plates 5 and 5'. Above washer 11 a yielding disk 4 is placed, and this disk may be provided with a centrally-located upwardly-projecting teat 4'.
65

All the above parts are assembled in the ferrule A, and the plates, disk, and washer rest upon the lugs 11.

The ball-retainers 1212 are composed of wire bent at their lower ends into widened loops 1313, which conform to the curvature of the main ball 9, which it is their function to confine in place, they extending a short distance 80 below the center of said ball. From their lower ends the wire constituting these retainers is bent inwardly at right angles, substantially as shown in Figs. 1 and 2, around the edges of the disk 4, and from thence radially 85 over said disk until they reach the central teat 4', when they are bent upwardly in contact with the outer surfaces of the latter, where they are confined by a ring 14 embracing them from the exterior. Thence this 90 wire is bent upwardly and spirally around a core 15, as shown at 16, to constitute the shank of the caster, which shank is adapted to hold it securely in the socket 17, formed in the lower end of the leg of furniture. In 95 the disposition of these retainers they occupy the spaces formed between the pairs of lugs 11, and from this point they extend upwardly through the notches 1010 in plates 5 and 5', where they are retained in position against 100 accidental displacement.

Referring to Fig. 2, which shows the caster in position, it will be seen how it is intended to operate. The shank being in position in

the socket 17 of the furniture-leg, the lower end of the leg rests upon the radial portions of the wire, which constitute the shank and retainers, and by reason of the weight applied 5 at this point the retainers are spread outwardly, thus relieving the ball 9 of the tight grip otherwise resulting from their position and construction. The result is that when the furniture is in position upon the floor 10 friction upon the balls 9 is reduced to a minimum, and the furniture may in consequence be moved with perfect ease over the surface of the floor. If occasion arises to lift the furniture, however, the pressure being removed 15 from these radial portions of the wire, the retainers spring inwardly, tightly engaging the balls 9 and preventing their accidental displacement. In this way the annoyance of the loss of the ball or roller when a piece of furniture is lifted is avoided and at the same 20 time friction is reduced and nearly eliminated altogether when the weight of the furniture is upon the caster, so that the furniture may be moved about the room wherein it is placed 25 with the utmost ease and facility.

What I claim as new, and desire to secure by Letters Patent, is—

1. A caster consisting of a ferrule having sockets therein balls retained in the sockets, 30 a main caster-ball upon which these ball-bearings rest and retainers embracing the main ball extending upwardly within the ferrule and terminating above said ferrule in the shank of the caster.

35 2. A caster consisting of a ferrule having ball-sockets therein, ball-bearings in these sockets, a main caster-ball upon which the ball-bearings turn and spring-retainers embracing the main ball, a portion of said retainers extending radially whereon they receive the weight of the furniture to cause them to spring outwardly from the main caster-ball.

40 3. A caster consisting of a ferrule having ball-sockets therein, ball-bearings in these sockets, a main caster-ball upon which the ball-bearings turn and spring-retainers embracing the main ball, a portion of said retainers extending radially whereon to receive 45 the weight of the furniture to cause an outward expansion of the retainers to release the caster-ball and the inner ends of the retainers bent to form a shank for the caster.

45 4. A caster consisting of a ferrule having ball-bearings therein, a main caster-ball upon which the ball-bearings turn, a yielding back-

ing above the bearings and retainers embracing the main ball and extending above the yielding backing and terminating in a shank for the casters.

60

5. A caster consisting of a ferrule having ball-bearings therein, a main ball upon which these bearings turn, a socket-plate above the bearings, a yielding backing above the socket-plate and retainers embracing the sides of the 65 main caster-ball and extending radially over the yielding backing where they receive the weight of the furniture thereon, to cause the retainers to spread under said weight.

6. In a caster, the combination with a ferrule provided with internally-projecting lugs and a plate above said lugs, said plate provided with concavities, balls seated in said concavities and between said lugs, ball-retainers extending between the pairs of lugs, 70 said ball-retainers being resilient, a caster-ball held by the retainers and preventing the displacement of the antifriction-balls, and a cushioning means above said plate.

7. In a caster, the combination with a ferrule provided with internally-projecting lugs, a plate above said lugs, said plate having concavities in its surface, balls seated in said concavities and between the lugs, recesses in the plate, resilient ball-retainers projecting 85 through said recesses, a ball retained thereby, said ball also retaining the antifriction-balls in place, a cushioning means above the plate, said ball-retainers forming a support for said plate and cushioning means and the ends of 90 said retainers forming the shank of the caster.

8. A cushioned caster comprising a ferrule having ball-bearings therein, a caster-ball, a cushioning device above said bearings, ball-retainers embracing the caster-ball and extending radially above the cushioning device terminating in the shank portion of the 95 caster, said radial portions adapted to receive the end of the leg of furniture and by the weight applied thereon, forcing the retainers 100 outwardly and when the leg is lifted, allowing said retainers to spring toward each other to prevent accidental displacement of the main caster-ball.

In testimony whereof I have signed my 105 name to this specification in the presence of two subscribing witnesses.
